UNITED STATES PATENT OFFICE

2,438,434

COLLAPSIBLE CONTAINER

Theodore Friedman, New York, N. Y.

Application February 20, 1945, Serial No. 578,844

1 Claim. (Cl. 220—8)

1

This invention relates generally to collapsible containers and more particularly to collapsible cups and similar receptacles.

It is an object of the present invention to provide an economical, efficient and practical collapsible receptacle, particularly where all of the parts are made of plastic composition.

It is a further object of the present invention to provide a collapsible cup made of telescoping plastic parts; and another object to provide a receptacle which will fit into said cup when collapsed and preferably maintained in fixed position, this receptacle being adapted to contain medicaments or other ingredients so that a person may be able to carry the same for mixing with liquid to be contained in the cup when placed in operable condition.

A still further object of the present invention is to provide a collapsible or foldable handle for the cup adapted to be attached to the cup when both the cup and the handle are in extended positions, the handle also serving as a measuring device, similar to a spoon.

Yet another object of the present invention is to adapt the said collapsible cup as a cover or closure for a bottle or other container.

These and further objects and advantageous features are accomplished by the novel and practical construction, combination and arrangement of parts hereinafter disclosed and illustrated in the accompanying drawings, constituting an essential part of the disclosure, and in which:

Fig. 1 is a view partly in section of a collapsible cup (in extended position) made in accordance with the invention;

Fig. 2 is a view partly in section of the said cup in collapsed position with cover applied thereto;

Fig. 3 is a view similar to Fig. 1 showing a collapsible cup made in accordance with the invention in a modified form;

Fig. 4 is a view similar to Fig. 2 (with cover removed) showing the collapsible cup illustrated in Fig. 3;

Fig. 5 is a top view of Fig. 4;

Fig. 6 is a view partly in section of a collapsible cup (in extended position) made in accordance with the invention in a still further modified form;

Fig. 7 is a view partly in section of the cup in Fig. 6 in collapsed position with a combined handle and spoon collapsibly positioned within the cup, a receptacle attached to one of the members of the cup, and a cover thereover;

Fig. 8 is a view of the cup seen in Fig. 6 with the combined handle and spoon (serving as a handle) being in operative position;

Fig. 9 is a view of the combined collapsible handle and spoon;

Fig. 10 is a sectional view taken through line 10—10 of Fig. 8;

2

Fig. 11 is a view of the combined handle and spoon in partially collapsed form;

Fig. 12 is a view taken through line 12—12 of Fig. 9;

Fig. 13 is a sectional view of a combined collapsible cup, and closure for a container, the upper part of the container being also shown in section;

Fig. 14 is a sectional view of the combined cup and closure in extended position; and

Fig. 15 is a partial view in section of the container.

Referring now more particularly to the drawings and, firstly with reference to Figs. 1 and 2, there is disclosed a member comprising the base 20 having connected thereto the annular flange 21 and the substantially ring section 22 forming a receptacle. Portion 22 has a tapering walled portion 23 connecting with a substantially vertical walled portion 24 turned outwardly as seen at 25 forming a channel 25a which receives the inwardly turned flange 26 of the tapering walled portion 27 of ring section 28. Portion 27 is spaced from flange 26 forming a channel 26a for receiving the outwardly turned flange 25. Connecting with portion 27 is the vertical walled portion 29 of ring section 28 which terminates in the outwardly turned flange 30 spaced from portion 29 similar to flange 25, forming a channel 30a for receiving the inwardly turned flange 31 of ring member or section 32, flange 31 being spaced from the tapering wall 33 providing a channel 31a for receiving the flange 30 of ring member 28.

It is evident that the ring members 32, 28 and 22 may be relatively telescopically collapsed as seen in Fig. 2, and may be relatively extended as seen in Fig. 1 in which case the respective ring flanges 26, 25, 30, 31 of the members will snugly fit into the corresponding channels 25a, 26a, 31a, 30a. The members 22, 28, and 32 are preferably made of plastic composition sufficiently resilient to permit an interlocking relatively tight fit at the joints formed by the said flanges and channels to maintain the cup in extended position. A cover 35 (Fig. 2) may be provided engaging the rim of the ring member 32.

According to Figs. 3 to 5, inclusive, the joints may comprise the interengaging threaded portions 40, 41; 42, 43; of the respective ring members 22a, 28a, 32a, the flange 21a extending outwardly from ring member 22a. After the ring members 22a, 28a and 32a have been unthreaded, they will relatively collapse or telescope.

Referring to the embodiment illustrated in Figs. 6—8, inclusive, walls of the ring sections 50, 51, 52 are frusto-conical and taper from top to bottom, and these sections or members progressively decrease in size from top to bottom permitting the same to nest when the cup is collapsed. Integrally connected to ring member 52 60 is the base 53 having the annular outwardly ex-

tending flange 54. The inner surface of member or section 52 carries graduations as clearly seen in Fig. 6. These graduations may also continue on the other ring members 51, 50. The amount of liquid poured into the cup may thus be measured.

Member 52 may be provided at its upper portion with internal threads 55 adapted for engagement with the external threads 56 of the upper portion of a receptacle 57 adapted to be positioned within the ring member 52 when the cup is collapsed.

A cover 60 is provided which also serves as a means for screwing and unscrewing the receptacle 57 from ring member 52. The threads 55 and 56 preferably loosely engage each other, and, therefore, a tight fit between the inner wall 61 of receptacle 57 and the wall 62 of the annular groove or channel 63 of cover 60 would be sufficient to produce the required friction to cause receptacle 57 to turn with the cover 60 during the screwing and unscrewing operations. However, in order to prevent any relative slipping between receptacle 57 and cover 60, grooves 64 may be provided in receptacle 57 for receiving lugs 65 on wall 62 of the cover.

Receptacle 57 may contain any desired ingredient 66 and may be graduated similar to ring member 52.

According to Figs. 6-10, inclusive, a combined handle and measuring device 70 may be provided. The embodiment illustrated in these figures comprises three hingedly connected sections 71, 72, 73, adjacent sections being joined together by pins 74 passing through pairs of ears 75. Section 73 provides a small scoop or bowl 76. Section 71 is curved outwardly as indicated at 71a and is provided with a lug 77 having a flaring tenon or tongue 78 adapted to fit into a mortise or socket 79 formed in ring member 50. Thus an interlocking joint is provided between the device 70 and cup. The rim or flange 54 is recessed as indicated at 80 providing a bearing for the tip of section 73 when the device 70 is extended to form the handle. The joints 75 are so disposed as to prevent collapsing of the device 70 when positioned to form a handle as seen in Fig. 8.

Device 70 may be folded at the joints as seen in Fig. 11 and may be located or positioned within ring member 52 on bottom 53 as seen in Fig. 7.

It is evident that the construction illustrated in Figs. 6-12 affords a convenient instrumentality for use in the administering of medicaments, which may be carried about the person. Receptacle 57 may contain powdered medicament to be measured off with the little bowl 76, the desired amount being placed within the cup and the latter extended for holding water or other liquid to be mixed with the powder, device 70 being employed for the mixing operation. The amount of liquid required may be measured, if the cup is graduated as seen in Fig. 6.

Referring to Figs. 13 to 15, inclusive, which illustrate the invention in a still further modified form, the device 80 comprises the nest of frusto-conical ring members 81, 82, 83, one fitting within another. The tapering walls of the members are such that when the cup is extended, the engaging walls at the extremity of the extension prevent separation of the members, as the same with the collapsible cup illustrated in Figs. 6-8, inclusive. Member 81 is provided with bottom 84 to which is connected

flange 85. Member 81 is further provided with the internal threads 86 adapted to engage the threads 87 on the neck 88 of container 89, when the cup 80 is collapsed. Container 89 may be provided with the conventional cork stopper 90. If desired, the member 81 may be employed as a closure for the container by providing a conventional seal between it and the rim of the bottle neck, thus eliminating the requirement of stopper 90.

It is preferably intended that the parts comprising the devices illustrated in the drawings be made of suitable plastic compositions, having sufficient resiliency or give in the case of the conical ring members to permit one ring member to be forced over its adjacent ring member, and yet not to easily cause separation of the ring members when the cup is extended. However, where the flange and bottom comprising the base of the cup are produced separately, as would be the case if the ring members were made of metal, then the ring members would be nested before the flange would be joined to the bottom of the cup, as is customary in forming the conventional collapsible cups.

Although the drawings and the above specification disclose the best modes in which I have contemplated embodying my invention, I desire in no way to be limited to the details of such disclosure, for in the further practical application of my invention many changes in the forms and proportions may be made as circumstances require or experience suggests without departing from the spirit of the invention within the scope of the appended claim.

Having thus described my invention, what I claim as new and desire to secure by Letters Patent is:

A collapsible container comprising a plurality of connected substantially ring shaped members varying in size whereby one member may be contained in another member when the container is collapsed, the innermost member being provided with a closed end having a flanged extension, a collapsible handle for said container, and cooperative means on one of said members and said handle for securing said handle to said container when they are in extended position, said handle having a small bowl portion bearing against said flanged extension when said handle is extended and to rest against said closed end when collapsed.

THEODORE FRIEDMAN.
